United States Patent Office.

WILLIAM K. RAIRIGH, OF RURAL VALLEY, PENNSYLVANIA.

Letters Patent No. 83,997, dated November 10, 1868.

IMPROVED IMPLEMENT.

The Schedule referred to in these Letters Patent and making part of the same.

To whom it may concern:

Be it known that I, WILLIAM K. RAIRIGH, of Rural Valley, in the county of Armstrong, and State of Pennsylvania, have, as I believe, invented new and useful Improvements in the Mechanic's Tool called the Hatchet; and I do hereby declare the following to be a full and exact description of the same, reference being had to the drawings that accompany and form a part of these specifications.

Figure 1, view of the box holding the various parts

Figure 2 presents the body of the implement, to which the handle is attached, with a portion of the front removed that the interior parts may be seen.

Figure 3, key for opening the jaws *i*, seen in fig 1.

Figures 6 and 8, blades of a hatchet, with tongues *g*, by which they attach to the central portion *A*.

Figure 4, a pair of nippers, having the tongue *g*.

Figure 5, a cold-chisel, also fitted to attach in the same way.

Figure 7, a vise or wrench.

The nature of my invention consists in placing, within the central portion *A* of a hatchet, a lock, as in fig. 1, and fitting the hatchet-blades and other tools for attaching to this by means of the tongues *g*, as illustrated in the drawings.

The red dotted lines, fig. 1, show how the cold-chisel, fig. 5, may be attached, and the attachment of all the others would be in the same manner.

At the two corners *xx* are two plane tongues, which fit into two corresponding grooves, *zz*, in the central portion *A*, and serve to keep the parts in place and

afford strength. This also is a feature of my invention.

The jaws *i* are held together by the coil-spring *h*. In fig. 1, the key is supposed to be applied, and the jaws *i* thereby opened, from which the tongue *g*, fig. 5, has just been removed.

The use of the article represented in fig. 7 gives us a vise or wrench.

This attachment alone provides an article of very great utility and convenience, presenting not only a wrench for turning nuts of various sizes, but also a vise for holding many little things that are to be drilled or filed.

A variety of tools fitted to be used in connection with a single handle, and all arranged in a convenient packing-box, will be of great practical advantage to many persons, not in the mechanic's shop merely, but to the farmer especially, who, for many little jobs, would otherwise be obliged to make a journey to a machine-shop.

What I claim as of my invention, and desire to secure by Letters Patent, is—

The implement herein described, constructed and arranged in the manner and for the purpose set forth.

In testimony whereof, I have signed my name to this specification, in the presence of two subscribing witnesses.

WM. K. RAIRIGH.
